UNITED STATES PATENT OFFICE.

CONRAD KUEBLER, OF CALAMUS, IOWA.

LOCK.

SPECIFICATION forming part of Letters Patent No. 712,078, dated October 28, 1902.

Application filed May 26, 1902. Serial No. 109,050. (No model.)

To all whom it may concern:

Be it known that I, CONRAD KUEBLER, a citizen of the United States, residing at Calamus, in the county of Clinton and State of Iowa, 5 have invented a new and useful Lock, of which the following is a specification.

This invention relates to locks or latches such as are used mainly upon barn-doors, gates, and the like, and it has special reference to such locking or latching devices which are used for locking the gate or door to which they are applied in a closed position and also for securing them in an open position.

My present invention consists in certain improvements in the detailed construction of the latch whereby the locking-bolt when drawn back against the tension of its spring shall be engaged by a lever, whereby it shall be held in its withdrawn position, the construction of 15 said lever being such that when the door is thrown either open or shut it shall be actuated to release the locking-bolt, causing the latter to engage with a suitable keeper, and thus retain the door either in an open or closed 20 position. The detailed construction of the device whereby these objects are attained will be hereinafter fully described and particularly pointed out in the claims.

In the accompanying drawings, Figure 1 is 25 a side view showing my invention applied to a door in position for operation. Fig. 2 is a horizontal sectional view, with dotted lines indicating the position of a door and lock when the door is open, the bolt of the lock being shown in engagement with its keeper. Fig. 35 3 is a horizontal sectional view showing the bolt withdrawn from the keeper and in engagement with the lever-catch or detent. Fig. 4 is a transverse sectional view taken on the 40 line 4 4 in Fig. 3.

Corresponding parts in all the figures are indicated by like characters of reference.

The casing 5 of my improved lock may be struck up or formed from sheet metal or cast-45 iron, and it is provided with flanges 6 to receive the screws or fastening devices by means of which it is in practice secured in operative position. The casing 5 is provided with guides 7 and 8 for the longitudinally-sliding 50 bolt 9, the guide 8 being in the nature of a perforated partition, through which the said bolt extends, a spring 10 being coiled upon said bolt between a shoulder 11 thereon and

the said partition to force or shoot the bolt in an outward direction. The inner end of 55 the bolt has a transverse perforation 12, through which extends a pin 13, which forms the handle by means of which the bolt is manipulated. One end of said pin is provided with a detachable cap or thumb piece 14, internally threaded to engage with the externally-threaded end of the pin. The part of the said pin extending through the perforation 12 in the bolt is of reduced diameter, thus forming a shoulder 15, which abuts against 65 the side of the bolt and prevents the pin from being drawn entirely through. By this construction the pin may be withdrawn or detached from the bolt to enable it to be passed through the slot 16, which must be formed for 70 its accommodation in the door upon which the device is adjusted for operation. The reduced end of the pin carrying the cap 14 extends through a slot 17 in the casing 5. The end of the pin 13 which projects through the slot 16 of the door is provided with an enlargement 75 18, by means of which it may be manipulated.

The casing 5 is provided near its outer end with a slot 19, adjacent to which lugs or ears 20 are formed for the passage of a pin or bolt 80 21, upon which the catch-lever or detent 22 is pivotally mounted. Said lever is provided near its outer end upon the side facing the bolt 9 with a tooth 23, adapted to engage with a tooth 24, formed upon the opposing face of 85 the bolt and serving to restrain the movement of said bolt in an outward direction under the impulse of the coiled spring 10. The lever 22 is also provided closely adjacent to its pivotal point with a cam-shaped projection 25, 90 adapted to engage the opposing beveled face of the tube 24 when the bolt 9 is withdrawn against the tension of the spring. The outer end of the lever 22 will thus be forced in the direction of the bolt, and the tooth 23, near 95 the outer end of said lever, will thus engage the outer end of the bolt, as will be seen in Fig. 3 of the drawings, said bolt being provided at its outer end with a notch 26, adapted to receive the tooth 23. The rear or inner 100 end of the lever 22 forms a handle 27, which when the bolt is shot may lie in contact with the casing. When the bolt is withdrawn against the tension of the spring and the lever is actuated by the beveled tooth or projection 24 engaging the cam-shaped projec-

tion 25 of said lever, the handle of the latter is moved outward from the casing to the position shown in Fig. 3, the tooth 23 being thus thrown into engagement with the notch at the 5 outer end of the bolt and retaining the latter in its withdrawn position. It will be observed that the tooth 23 has been particularly described as being located "near" the outer end of the lever. This is important, because the 10 extreme outer end of said lever must be free to engage the keeper of the bolt, as will be presently described.

The keeper, which is designated by 29, consists of a hasp or staple suitably secured to 15 the door-frame in a convenient position to be engaged by the bolt 9. A similar keeper 30 is secured to the wall or frame of the building in a suitable location to be engaged by the bolt when the door is thrown open.

20 The operation of my invention will be readily understood. The relative location of the parts when the door is closed has been shown in Figs. 1 and 2. When it is desired to open the door, the bolt 9 is withdrawn against the 25 tension of the spring by means of the pin or handle 13, thus disengaging it from the keeper and at the same time actuating the lever 22 by the beveled tooth 24 engaging the cam-shaped projection 25, thus causing the tooth 23 to engage the outer end of the bolt and retain the latter in its withdrawn position. Now 30 in case the door is thrown wide open the end or handle 27 of the lever will strike against the wall of the building, thus swinging the 35 lever upon its pivot, releasing the tooth 23 from its engagement with the outer end of the bolt, causing the latter to be shot by the spring 10 into engagement with the keeper 30, and thus securing the door in an open position. If, on the other hand, the door be 40 thrown shut, the extreme outer end of the lever 22 beyond the tooth 23 will impinge upon the outer side of the keeper 29, thus releasing the lever and causing the bolt to be shot 45 into engagement with the keeper and securing the door in its closed position.

As will be seen from the foregoing description, my improved locking device is simple in construction, easily operated, is capable of 50 being reversed or applied with equal facility to right as well as to left hand doors, it is not liable to get out of order, the operation of the lever-catch or detent is automatic, and said catch or detent is automatically released, so 55 as to cause the bolt to be shot when the door is thrown either open or shut.

Having thus described my invention, I claim and desire to secure by Letters Patent of the United States—

60 1. The combination of a casing, the spring-actuated bolt arranged slidably therein and having a beveled tooth or projection, and a lever or catch facing said bolt and having a tooth or projection adapted to engage the 65 front end of the bolt, substantially as set forth.

2. The combination of the casing, the slid-

ing spring-actuated bolt having a beveled tooth and the lever provided on opposite sides of its fulcrum with a cam-shaft projection 70 adapted to be engaged by said beveled tooth, and with a tooth adapted to engage the latter or the outer end of the bolt according to the position of the latter, substantially as set forth.

75 3. The combination of the casing, the sliding spring-actuated bolt having a beveled tooth, the lever having a beveled projection on one side of its fulcrum adapted to be engaged by said beveled tooth and provided on 80 the opposite side of its fulcrum with a tooth adapted to engage the outer end of the bolt or the tooth upon the latter, and a keeper adapted to receive the bolt and to engage the end of the lever projecting beyond the tooth 85 thereon, substantially as set forth.

4. The combination of the casing, the sliding spring-actuated bolt having a beveled tooth, a lever having a cam-shaped projection adapted to be engaged by the said beveled 90 tooth and provided on the opposite side of its fulcrum with a tooth adapted to engage the outer end of said bolt or the tooth upon the latter, according to the position of said bolt, and a handle formed by the inner end of the 95 lever and adapted to lie in contact with the outside of the casing when the bolt is shut, and to be moved outward from the casing when the bolt is drawn, substantially as set forth.

100 5. The combination of the casing, the sliding spring-actuated bolt having a beveled tooth, the lever provided on opposite sides of its fulcrum with a cam-shaped projection and with a tooth, said tooth being located at a distance from the outer end of the lever, a handle upon said lever lying outside the casing, 105 keepers adapted to be engaged by the bolt, and a handle for the latter, substantially as set forth.

110 6. The combination with a spring-actuated bolt, of a lever having means for engaging said bolt to retain it in a drawn position, said lever being provided with projecting parts on opposite sides of its fulcrum adapted to engage fixed points of contact and thereby to release the bolt for engagement with a keeper, substantially as set forth.

115 7. The combination of a casing attached to a swinging bracket, a spring-actuated bolt 120 within said casing, a lever having means for engaging said bolt to retain the same in a drawn position, said lever being provided with projections adapted to engage fixed points of contact and thereby to release the 125 bolt for engagement with its keeper, substantially as set forth.

In testimony that I claim the foregoing as my own I have hereto affixed my signature in the presence of two witnesses.

CONRAD KUEBLER.
